FURNACE SEAL

Harold R. Purcel, Philadelphia, Pa., assignor to
 The Allen-Sherman-Hoff Company, Philadelphia, Pa., a corporation of Pennsylvania

Application July 5, 1940, Serial No. 343,934

5 Claims. (Cl. 110—165)

This invention relates to steam boiler furnace structures or the like and more particularly to sealing means for closing an open joint between the furnace bottom and an ash hopper or receiving vessel disposed below the furnace outlet, which sealing means will effectively prevent the infiltration of air into the furnace while permitting the necessary relative expansion and contraction of the parts.

The tendency in modern boiler practice is toward the employment of much greater draft than has previously been used. Certain modern furnaces have a draft as high as 2" of water as distinguished from .1" to .15" which was usual in the older types of furnaces. With the low draft values previously employed sliding seal structures of various types were employed between the furnace bottom and the ash hopper disposed therebelow and with the low draft furnaces infiltration of air through such sliding seal arrangements was not particularly serious. However, in the modern high draft furnaces, the old type sliding seal permits excessively large quantities of air to be drawn into the furnace between the sliding joints with resulting substantial reduction in furnace efficiency.

It is among the objects of the present invention to provide a furnace seal which will effectively and positively prevent infiltration of air between the furnace bottom and the ash hopper while permitting expansion and contraction of the furnace walls in any direction and in any degree encountered in practice. Other objects of my invention include the provision of a water seal for furnace bottoms which is protected from the radiant heat from the furnace interior and which will remain completely effective regardless of uneven expansion of the furnace walls in different directions; the provision of a water seal for furnace bottoms which is simple in form, may readily be inspected and repaired or replaced when necessary, and which will permit dewatering of the ash hopper while maintaining the seal; and the provision of a furnace seal structure which may readily be adapted to various types of furnaces.

The above and other objects of my invention will appear from the following description of several embodiments thereof, reference being had to the accompanying drawings, in which—

Figure 1 is a horizontal cross-sectional view of a furnace bottom incorporating my invention, taken substantially on line 1—1 of Figure 2.

Figure 2 is a vertical cross-sectional view of the furnace bottom and ash hopper shown in 55

Figure 1 taken on line 2—2 of Figure 1 and illustrating one form of my water seal structure.

Figure 3 is a transverse cross-sectional view taken on line 3—3 of Figure 1.

Figure 4 is an enlarged fragmentary vertical cross-sectional view of my water seal arrangement taken on line 4—4 of Figure 1.

Figure 5 is a view generally similar to Figure 4 but taken on line 5—5 of Figure 1 and showing the water inlet and outlet connections to the seal trough.

Figure 6 is an enlarged fragmentary horizontal cross-sectional view taken at the corner of the furnace bottom shown in Figures 1 and 2 and illustrating the flexible sealing connections between the seal plates.

Figure 7 is a vertical cross-sectional view of the corner seal construction taken on line 7—7 of Figure 6.

Figure 8 is a vertical cross-sectional view of another form of furnace bottom in which the furnace outlet is circular in form and the seal is correspondingly circular.

Figure 9 is a vertical cross-sectional view of a modified form of my invention associated with a furnace having water cooled walls supplied with lower headers.

Figure 10 is a fragmentary plan view of the apparatus of Figure 9 taken on line 10—10 of Figure 9.

Figure 11 is a partial end view from the right of Figure 9.

The furnace bottom shown in Figures 1, 2 and 3 is rectangular in form and includes side walls 1 and 2 and end walls 3 and 4. The outlet defined by these walls conveys the products of combustion from the furnace into the ash hopper situated therebelow. This hopper has sloping end walls 5 and 6 and side walls having vertical portions 7 and 8 which join sloping portions 9 and 10. A grid 11 may be disposed in the hopper and suitable means, not shown, may be provided for maintaining a water level at 12 in the hopper. The products of combustion fall into the water in the hopper and are removed through the pipe 13 by the pump 14 for conveyance to any suitable place of disposal.

The upper edges of the hopper walls are spaced from the lower edges of the furnace walls to permit relative vertical movement thereof due to contraction and expansion of the furnace structure during operation. Furthermore, the hopper walls are disposed outside of the furnace walls and spaced therefrom to permit lateral and endwise expansion of the furnace walls. This con-

struction, as is clearly seen in Figures 2 and 3, leaves a substantial space between the furnace walls and the hopper walls throughout their entire perimeter and in order to seal this gap and prevent infiltration of air therethrough I provide a water seal comprising a trough T extending entirely around the hopper structure and supported on projecting flanges or projections 15 which form a part of the supporting structure for the hopper walls. The trough T is preferably endless and is open at its top to permit the entry of the sealing fins 16 which are secured to downwardly projecting webs 17 by bolts 18. Leakage around the top of webs 17 is prevented by welding or otherwise securing the top of the webs to the bottom structural members of the furnace walls, as seen in Figures 4, 5 and 7. Suitable gaskets 19 are preferably employed between the webs 17 and the fins 16 to form leak-proof joints therebetween. The fins 16 extend down into the trough T which is provided with a plurality of water inlet pipes 20 having control valves 20' for regulating the flow of water therethrough and overflow outlet pipes 21 extending into the interior of the hopper. The fins 16 are of such length that they will always project into the body of water in the trough T and, regardless of expansion or contraction of the furnace bottom or movement thereof up and down relative to the hopper, a positive seal will be maintained at all times between the hopper and the furnace bottom.

At the corners of the rectangular furnace bottom illustrated in Figures 1 and 2 the seal plates 16, which are co-extensive with the furnace walls, are spaced apart and connected by flexible members 22 which are secured to the sealing fins and webs 16 and 17 in a leak-proof manner by screws 23 and binding strips 24. The flexible members 22, which may be of impervious, heat resisting, impregnated glass fabric or other suitable material, extend from the bottom of the fins 16 up into abutting relation with the projecting flange 25 of the furnace bottom frame structure (see Fig. 7).

It will be observed that the flexible fabric corner joints of my sealing fins permit the inevitably unequal expansion of the furnace walls in different directions to take place without any strain or load being imposed upon the parts. Furthermore, they maintain an effective seal substantially preventing infiltration of the air at the corners.

Referring particularly to Figures 4 and 5, it will be observed that the trough T is disposed entirely outside of the walls of the ash hopper and is effectively protected from radiant heat from within the furnace bottom by the hopper walls themselves.

It is noted that the water level on the inside of the sealing fins 16 is shown as higher than that on the outside and it will be understood that this represents the operating condition of the furnace, the water level difference being due to the reduced pressure existing inside of the furnace structure. Although the overflow from the trough T is illustrated as being conducted through pipes 21 into the hopper, it will be understood that in some instances it may be desirable to discharge the hopper overflow outside of the hopper and this can be accomplished by providing suitable overflow pipes from the outer wall of the trough T.

In Figure 8 I have illustrated my furnace seal as applied to a furnace bottom having a circular

outlet opening 26. A circular fin 27 is secured to the furnace bottom, as by welding at 28, and projects down into the annular trough 29 supported on the hopper top 30. An inlet pipe 31, equipped with a suitable control valve 32, supplies water to the trough 29 and the overflow is directly over the lip of the upwardly projecting inlet wall 33 of the hopper or ash receiving chamber 34. Thus, the overflow of water from the trough 29 in this arrangement will cool the nose of the hopper and protect the refractory material from excessive heat. With this arrangement a perfect seal is maintained at all times between the parts and the trough water performs the dual function of maintaining the seal and cooling the entering throat of the ash receiving chamber.

In Figures 9, 10 and 11 another embodiment of my invention is illustrated in which the seal plates are secured to the lower headers, seen at 36, 37 and 38, of the water cooled walls of a furnace bottom. These headers form a part of the furnace walls and it will be understood that suitable refractory enclosing structures are provided to complete the furnace chamber although the bottom edges of the furnace outlet are defined by the headers 36, 37 and 38. Seal plates 39 and 40 are secured to and supported by the transverse headers 36 and 38 and seal plates 41 are supported by the headers 37. (Only one header 37 is shown in the drawings but it will be understood that another similar header may be disposed directly opposite the header 37 shown in Figure 9.) The plates 41 extend around the corner indicated at 42 and, as is seen at 43 in Figure 11, end approximately in line with the inner edge of the header 37. Space is, of course, provided between the ends of the headers 36 and 38 and the sides of the headers 37 and a gap occurs between the ends of the seal plates 39 and 40 and the angle extensions 43 of the seal plates 41. These gaps are closed by flexible connecting members 44, preferably made of impervious fabric.

The ash collecting hopper walls are disposed below the headers 36, 37 and 38 and, as illustrated, include spaced inner and outer double walls 45 and 46. These walls extend from the bottom 47 of the hopper to the top thereof and perform the dual function of providing a trough into which the seal plates 39 and 40 extend and forming water cooled walls for the hopper. Reinforcing channels 48, suitably perforated to provide free circulation of water in the trough, may be provided and an outlet for the hopper is indicated at 50 closed by a suitable gate 51. Spray nozzles 52 are connected to pipes 53 extending through suitably sealed apertures in the water cooled hopper walls. Water is supplied to the combined sealing troughs and water cooled hopper walls through the pipes 54 and 55 and overflow from the trough occurs through suitably located pipes 56. At the bottom of the water cooled walls a drain pipe 57, controlled by a valve 58, permits complete emptying of the trough when desired.

It will be understood that the drawings illustrating the various embodiments of my invention are somewhat diagrammatic and that in actual furnace constructions numerous details would be included which are not shown as they do not pertain to the present invention. Where the term "furnace bottom" is used in the specification and claims it is intended to mean either the furnace walls as shown in Figures 1 to 8 inclusive, the bottom headers of water cooled walls

as shown in Figures 9, 10 and 11, or other parts of the furnace structure adjacent the bottom outlet thereof to which the sealing flanges are attached to complete a water seal with the trough associated with the hopper disposed below the furnace outlet.

Although I have described the illustrated forms of my improved furnace seal in considerable detail it will be understood by those skilled in the art that my invention is readily adaptable to other types and shapes of furnace bottom outlets and modifications may be made in the arrangement and form of the parts without departing from the spirit of my invention. I do not, therefore, wish to be limited to the specific embodiments herein disclosed but claim as my invention all forms thereof coming within the scope of the appended claims.

I claim:

1. In a seal for the joint between a furnace bottom and a hopper disposed therebelow, a trough supported by said hopper, a plurality of fin members secured in air-tight contact to said furnace bottom and extending into said trough, the adjacent ends of said fin members being spaced apart to permit relative movement thereof, a flexible, substantially impervious member connecting said fin ends and extending into said trough, and means for maintaining a body of water in said trough above the bottom edge of 30 said fins and flexible member.

2. In a combination, a furnace bottom having a generally rectangular outlet opening, downwardly projecting fins supported in air-tight contact on the furnace outside of and adjacent 35 said outlet, the ends of said fins being spaced at the corners of said rectangular opening, flexible, air impervious material connecting the adjacent ends of said fins at said corners, a hopper below said outlet, a trough supporter by said hopper below said fins, said fins and flexible corner connections extending down into said trough, and means for supplying water to said trough to form a seal.

3. A seal between a furnace bottom having an outlet opening and a hopper disposed therebelow and having walls extending around said furnace outlet, including a trough associated with said hopper walls and extending around said furnace outlet, fin means carried by said furnace bottom in air-tight contact therewith and extending into said trough, and means for supplying water to said trough, said fin means including a plurality of seal plates having spaced ends and flexible, substantially impervious portions connecting said spaced ends.

4. In combination, a furnace structure having a bottom outlet opening and downwardly projecting fins extending around said opening and having air-tight contact with said furnace structure, a hopper below said outlet opening having spaced inner and outer walls forming an open topped double wall structure extending around and below said outlet opening, said fins extending into the space between said walls, and means for maintaining water in said space at a level above the bottom edge of said fins, said fins including spaced rigid sections connected by flexible substantially impervious sections.

5. In combination with a steam generating furnace having walls defining an ash discharge opening, a hopper below said ash discharge opening and having a top opening to receive ash from said furnace, a receptacle for water surrounding the hopper adjacent to said top opening and having substantially air-tight contact with said hopper, a plurality of separate fin means secured in substantially air-tight connection to said furnace around the outside of said ash discharge opening, said fin means projecting into said water receptacle between the side walls thereof, flexible, gas impervious means connecting adjacent ends of said fin means, and means to maintain a level of water in said receptacle above the bottom of said fin means.

HAROLD R. PURSEL.
